UNITED STATES PATENT OFFICE.

WILLIAM H. SCHENCK, OF STERLING, COLORADO.

SEEDING-MACHINE.

SPECIFICATION forming part of Letters Patent No. 392,368, dated November 6, 1888.

Application filed February 4, 1888. Serial No. 262,999. (No model.)

To all whom it may concern:

Be it known that I, WILLIAM H. SCHENCK, of Sterling, in the county of Logan and State of Colorado, have invented a new and Improved Seeding-Machine, of which the following is a full, clear, and exact description.

This invention relates to seeders, the object of the invention being to provide for the formation of a drill which will close without the aid of a drill or furrow closer after the passage of the drill-opening devices, the invention consisting in the construction and arrangement of parts hereinafter fully described and claimed.

Reference is to be had to the accompanying drawings, forming a part of this specification, in which similar figures of reference indicate corresponding parts in all the views.

Figure 1 is a sectional side view of a portion of the seeder, the view being taken on a line corresponding with that of the line $\alpha\alpha$ of Fig. 2. Fig. 2 is a sectional plan view taken on line yy of Fig. 1, and Fig. 3 is a cross-sectional view of the disks on line zz of Fig. 1.

In constructing such a seeder as the one forming the subject-matter of this application I provide a number of disk-carrying frames, which are made up of bars 10, the forward ends of which bars are united, the bars being bent outward from the point of union to be connected at 11 to the adjacent bars. Back of the point 11 the bars are bent outward at a slight angle and then bent inward at 12, so that they will run in lines that are substantially parallel, and then again inward at 13 and outward at 14, the rearwardly-extending ends 15 being united.

Just in advance of the angle 12 there are mounted studs 16, which extend inward at about right angles from the bars 10, and upon these studs are journaled disks 20, that are formed with outwardly-flaring rims 17, the approaching ends of the hubs 18 of the disks 20 being recessed to receive the heads of the studs 16, while upon the outer ends of the studs 45 there are mounted sheet-metal shields 19, to prevent the entrance of grit or dirt. By mounting the disks as above described the peripheral edges of the rims 17 will closely approach or touch at the point a , (see Figs. 1 and 3,) so that as the seeder is drawn forward in the di-

rection of the arrow shown in Fig. 2 a narrow and comparatively deep drill will be opened in the ground.

In order that the disks may be held down to their work, I provide an upwardly-extending standard or rod, 22, upon which there are placed a number of weights, 23. A seed-delivery tube, 24, passes downward between the disks 20 to a point just above the level of the ground, the lower end of this tube being carried forward to a position such that the grain will pass therefrom in advance of the point at which the disks leave the ground. This tube 24 is supported by a bracket, 25. In practice a number of sets of disks would be united, as shown in the drawings. In order that the disks may be cleared from any material which might adhere to them, I provide clearers 26, that are connected to the bars 10 just behind the bends 13.

With such a seeder as the one above described I am able to cut through sod, corn-stalks, or any other obstruction of like nature, and by making a narrow furrow, in which the seed is deposited, I avoid the necessity of employing a dragging furrow-closer, thus materially lightening the draft.

Having thus fully described my invention, I claim as new and desire to secure by Letters Patent—

The combination, with the frame formed of the bars 10, connected at 11, diverging therefrom rearwardly to the points 12, and thence extending in parallel approximately straight lines to the points 13 and converging at 14 and secured together, of the diagonally-projecting studs 16, secured to the inner sides of the bars 10 in front of the points 12, the disks 17, journaled thereon and contacting, or nearly so, at the point a and diverging rearwardly, the scrapers 26, secured to the inner sides of the parts 13 of the bars, and the bar 25, secured to the bars in front of the disks and extending upward and over the disks, and the spout extending downward therefrom between the disks in rear of their axes.

WILLIAM H. SCHENCK.
